WILLIAM D. BREWSTER, OF SYRACUSE, NEW YORK, ASSIGNOR TO NATIONAL BRAKE COMPANY, INCORPORATED, OF BUFFALO, NEW YORK, A CORPORATION OF NEW YORK.

HAND-OPERATED BRAKE MECHANISM.

1,111,640.

Specification of Letters Patent.

Patented Sept. 22, 1914.

Application filed January 27, 1914. Serial No. 814,680.

To all whom it may concern:

Be it known that I, WILLIAM D. BREWSTER, of Syracuse, in the county of Onondaga, in the State of New York, have invented new and useful Improvements in Hand-Operated Brake Mechanism, of which the following, taken in connection with the accompanying drawings, is a full, clear, and exact description.

10 This invention relates to certain improvements in hand-operated brake mechanism for motor-driven and other cars requiring a reliable emergency brake and refers more particularly to the means for transmitting motion from the staff to the brake-operating table.

The space available below the platform of an ordinary surface car for receiving extra mechanism is necessarily limited, inconvenient of access and allows an accumulation of excessive quantities of dust and other foreign matter upon any mechanism which may be supported in such space, and one of the main objects of my present invention is to 25 divide the brake-operating mechanism at the floor line so that only the cable-operating drum is supported in the space below the platform while the driving mechanism is supported above the platform and connected 30 to the drum therethrough, thereby bringing the cable-operating drum closer to the bearings on the platform and reducing the strain upon said drum and its driving shaft as well as upon the supporting frame for said 35 shaft.

Another object is to make the supporting frames for the drum and its driving mechanism separate so that they may be applied to the lower and upper surfaces of the platform and adjusted relatively to each other to compensate for different thicknesses of platforms.

A further object is to provide simple means for taking up the slack of the brake-operating cable so as to enable the operator to apply the brakes instantly upon an initial movement of the brake staff, thereby obviating the necessity of rotating the shaft several turns before the cable is sufficiently tight to apply the brakes.

Another object is to provide the holding pawl for the staff with a retracting spring

concealed therein and operating to hold the pawl in engagement with the ratchet wheel on the staff.

Other objects and uses relating to specific parts of my invention will be brought out in the following description:

In the drawings—Figure 1 is a top plan, partly in section of my improved brake-operating mechanism, showing a portion of the top of the gear case and underlying gear broken away to disclose the spring for taking up the slack of the cable. Fig. 2 is a transverse vertical sectional view of the same mechanism taken on line 2—2, Fig. 1, showing a portion of the platform of a car upon which the brake-operating mechanism is mounted. Fig. 3 is an enlarged horizontal sectional view through the holding pawl for the ratchet on the staff, showing the retracting spring therein. Fig. 4 is a perspective view of the adjacent ends of the detached sections of the brake staff showing the universal joint.

The brake-operating mechanism, forming the subject matter of my present invention, is adapted to be secured to the platform or floor—A—of a car and comprises a drum-supporting frame—1— and a gear case—2—, both of which are secured respectively to the under side and upper side of the platform—A—by clamping bolts—3— passing through the platform and apertured ears or lugs—4— and—5— on the frame and gear case to firmly hold those parts in operative position or in fixed relation to each other and to the platform.

The drum-supporting frame—1—is preferably made in sections and consists of a base plate—6— and a cup-shaped body—7— having openings through its sides to permit the passage of a brake-operating cable—8— therethrough as will be herein-after more fully described.

The cup-shaped body—7— having its upper end provided with the ears or lugs—4— while the plate—6— is clamped between said lugs and the underside of the platform by means of the bolts—3—.

The gear case—2—is made in sections and comprises a base plate—9— and an inverted cup-shaped section—10— having the edges of its open side bearing upon the

upper face of the plate —9— which in turn is clamped between the section —10— and upper surface of the platform —A— by means of the bolts —3—, thereby forming a dust-proof housing for the inclosed operating parts presently described.

A vertical shaft —11— is journaled at its lower end and intermediate portion in suitable bearings —12— and —13— in the frame sections —7— and —6— while the upper end of the shaft extends through an opening in the platform and some distance above the same and is journaled in a bearing —14— on the base plate —9— of the gear case, said bearing extending into the opening in the platform but is spaced apart at —15— from the base plate —6— of the lower frame —1— a sufficient distance to compensate for slight variations in the thickness of different platforms to which the brake mechanism may be applied.

The portion of the shaft —11— between the bearings —12— and —13— is angular or square in cross section and upon this angular portion is mounted a winding drum —16— for the cable —8—, said drum having its lower end provided with a furcated lateral offset —17— having a series of radial openings at different distances from the axis of the drum for receiving a pin —18— by which the cable may be attached to the drum at different distances from its axis according to the position of the pin in one or the other of the apertures in the offset portion —17—.

The upper portion of the drum —16— is cylindrical and of considerably less diameter than the distance from the axis to the pin —18—, the object of the offset portion —17— being to force the brakes to their braking positions instantly upon a slight turning movement of the drum as produced by the operating mechanism hereinafter described whereupon the cable engages the periphery of the cylindrical portion of the drum when the axis where the leverage is reduced and the power of application of the brakes materially increased. The upper end of the shaft —11— above the bearing —14— is also angular in cross section and upon this angular portion is fitted a relatively large gear —20— having an annular recess —21— in its lower side for receiving a coil spring —22— for taking up the slack of the chain in a manner presently described, the inner end of the spring being attached to a stud —23— rising from the base plate —9— of the gear case while the outer end is attached to a stud —24— on the under side of the web of the gear —20—, the top of the gear being substantially flat and open at the corresponding end of the shaft —11— which is spaced apart from the underside of the top of the case section —10— to allow the en-

tire gear case to be moved downwardly toward the drum-supporting frame a short distance in case there should be a slight variation in the thickness of the platform.

The vertical brake staff —25— is journaled at its lower end in suitable bearings 70 in the lower and upper sections —9— and —10— on the gear case some distance to one side of the periphery of the gear —20— and is provided with a gear —26— located within the gear case and meshing with said gear.

The portion of the brake staff just above the top of the gear case is angular in cross section and upon this angular portion is mounted a ratchet wheel —27— having its hub resting upon the upper side of the case section —10— which is also provided with a vertically projecting stud —28— for receiving and supporting a holding pawl —29—, the latter being spring-pressed into engagement with the teeth of the ratchet wheel —27— by a spring —30—. This spring is seated in a slot —31— opening from the outer end of the stud —28— and extends radially in opposite directions and 90 equidistant from the stud in a longitudinal recess —32— in the underside of the pawl as shown more clearly in Fig. 3, the ends of the recess being reduced in width to approximately the thickness of the spring 95 so as to bear against both sides thereof.

It is evident from the foregoing description that the pawl is actuated by both ends of the spring which is adjusted so as to maintain the pawl in holding engagement 10 with the teeth of the ratchet wheel under yielding pressure, thereby permitting the ratchet wheel to be rotated in the direction indicated by arrow X for winding the cable on the drum —16— and preventing the rotation of said drum and its operating mechanism in the opposite direction. The object in placing this spring within the recess in the underside of the pawl is to exclude dust therefrom and prevent injury thereto by contact with external objects and at the same time bringing the pawl and spring into a more compact space than would be the case if the spring were located at the outside of the pawl. The brake staff —25— is preferably made in sections connected by a universal joint to prevent binding of the staff in its bearings in case the platform should settle or warp from its original position.

As previously stated, the object of the coil 120 spring —22— is to automatically take up any slack in the cable —8— and for this purpose the spring is placed under constant tension, tending to drive the gear in the same direction as would be produced by the staff in winding the cable on the drum, it being understood that this spring tension is just sufficient to take up such slack and to

thereby keep the brake shoes close to the wheels ready for instant braking action upon the slightest initial rotation of the 5 brake staff. By means of this automatic take-up device, the hand brake is always ready for emergency application of the brakes without the necessity of rotating the brake staff one or more turns as shown before the brakes are applied.

10 The operation of the device is made apparent in the foregoing description, and although the drum case and gear case are shown as applied respectively to the lower and upper surfaces of the floor and constitutes an important feature of my invention, I do not wish to limit myself to this construction and arrangement nor to the details shown and described.

Another important feature in the operation of the spring —22— is that it is placed under comparatively high tension during the winding of the cable on the drum to apply the brakes so that when the power employed in the operation of the brakes is released and the pawl —29— tripped, the spring reverses the operation of the brake mechanism and forcibly and rapidly restores it to its normal position, thereby instantly releasing the brakes and at the same time always maintaining a taut cable even when the brakes are released.

What I claim is:

1. In combination with the platform of a car, brake-operating mechanism comprising a vertical shaft extending through the platform, separate bearings for the shaft secured respectively to the lower and upper sides of the platform and relatively adjustable to compensate for different thicknesses of platforms, a brake-operating cable, a winding drum therefor, and driving means for the shaft above the platform.

2. In combination with the platform of a car, a drum-supporting frame secured to the underside of the platform, a brake-operating cable, a winding drum for the cable within said frame, a vertical driving shaft for the drum extending through and above the platform, a gear case secured to the upper side of the platform, intermeshing gears within the gear case, one of said gears being secured to the vertical shaft, and a brake-staff secured to the other gear for driving the gears and brake drum.

3. In combination with the platform of a car, a drum-supporting frame secured to the underside of the platform, a gear case secured to the upper side of the platform and spaced apart therefrom to allow for variations in the thicknesses of different platforms, a brake-operating cable, a winding drum for the cable within the frame, gears within the gear case, a vertical shaft connecting the drum and one of the gears through the plat-

form, and a brake-staff connected to the other gear for driving the gears and drum.

4. Brake-operating mechanism comprising a cable, a winding drum therefor, a driving shaft for the drum, a brake staff, means for transmitting motion from the 70 brake staff to the drum shaft, and means co-acting with said transmitting means for turning the shaft and drum to automatically wind the cable thereon for taking up any slack in the cable.

5. Brake-operating mechanism comprising a cable, a winding drum therefor, means for rotating the drum including a brake staff, and a spring tensioned to rotate the 75 drum to wind the cable thereon and to take up the slack therein.

6. Brake-operating mechanism comprising a cable, a winding drum therefor, a drum shaft, a gear on the shaft chambered in one side, a coil spring in the chamber 85 having one end attached to the gear, a fixed support for the other end of the spring, said spring being tensioned to rotate the shaft in a direction to wind the cable on the drum for taking up the slack therein, and 90 means for rotating the gear.

7. Brake-operating mechanism comprising a drum, a cable attached to the drum, means for rotating the drum in one direction to wind the cable thereon, and a spring tensioned to drive the drum-operating mechanism in the same direction to automatically take up the slack in the cable.

8. In combination with the platform or floor of a car, brake-operating mechanism 100 comprising a drum case and a gear case secured respectively to the lower and upper sides of the floor, a drum in the drum case, a cable attached to the drum, a drum shaft extending through the floor into the gear case, a gear in the gear case mounted on the shaft and chambered in one side, a coil spring in the chamber having one end attached to the gear case and its other end attached to the gear, said spring being tensioned to rotate the gear in one direction to wind the cable on the drum for taking up the slack, a brake staff having a pinion in the gear case meshing with the gear for driving the gear and rotating the drum in the same direction as the spring, and holding means for the brake staff comprising a ratchet wheel secured thereto, and a pawl pivoted to the top of the gear case and spring-pressed into engagement with the ratchet wheel.

9. Brake-operating mechanism comprising a cable, a winding drum therefor, driving means for the drum, and a spring placed under tension by the winding operation of the drum to rewind said drum and restore the drum to its starting position for releasing the brakes when the driving means is released.

10. Brake-operating mechanism comprising a cable, a winding drum therefor, driving means for the drum, and a spring placed under tension by the winding operation of 5 the drum to rewind said drum and restore the drum to its starting position for releasing the brakes when the driving means is released, said spring being normally ten-

sioned to automatically take up the slack of the cable.

In witness whereof I have hereunto set my hand this 17th day of November, 1913.

WILLIAM D. BREWSTER.
